(57) **CLAIM**

The ornamental design for a vacuum gripper with battery as shown and described.

DESCRIPTION

FIG. 1 is a top perspective view of a vacuum gripper with battery, showing my new design;

FIG. 2 is a top perspective view of the vacuum gripper with the battery removed;

FIG. 3 is a bottom perspective view of the vacuum gripper and battery;

FIG. 4 is a top elevational view thereof;

FIG. 5 is a left elevational view thereof;

FIG. 6 is a rear elevational view thereof;

FIG. 7 is a right elevational view thereof;

FIG. 8 is a bottom elevational view thereof;

FIG. 9 is a front elevational view thereof;

FIG. 10 is an enlarged top elevational view of the battery;

FIG. 11 is a left elevational view thereof;

FIG. 12 is a rear elevational view thereof;

FIG. 13 is a right elevational view thereof;

FIG. 14 is a bottom elevational view thereof;

FIG. 15 is a front elevational view thereof; and,

FIG. 16 is a bottom perspective view thereof.

The broken lines in the drawings illustrate a portion of the vacuum gripper with battery which forms no part of the claimed design.
